PRINTING PRESS AND THE LIKE

Leroy Q. Presby, Melrose, Mass., assignor to
American Stay Company, East Boston, Mass.,
a corporation of Massachusetts

Application July 27, 1939, Serial No. 286,827

2 Claims. (Cl. 101—247)

My invention relates to web treating apparatus, particularly but not exclusively to printing presses.

The invention has among its objects the provision of apparatus having operating means for progressively acting upon a lengthwise fed web, and means for causing relative movement between the web and operating means for placing the web in and out of presented relation to the operating means. The invention however will be best understood from the following description when read in the light of the accompanying drawings, the scope of the invention being more particularly pointed out in the appended claims.

In the drawings:

Fig. 1 is a front elevation of a printing press according to the invention, with parts omitted;

Fig. 2 is a side elevation of the printing press according to Fig. 1, as viewed from the left, with parts omitted;

Fig. 3 is a section on the line 3—3 of Fig. 1 showing parts according to Fig. 2 in a different operative position, and with parts omitted;

Fig. 4 is a section on the line 4—4 of Fig. 1, with parts omitted;

Fig. 5 is a section on the line 5—5 of Fig. 2, with parts omitted and parts broken away; and

Fig. 6 is a section on the line 6—6 of Fig. 2, with parts omitted.

The invention is particularly applicable to printing presses of the type shown in applicant's Patent 2,107,647, February 8, 1938, in which a length of web is led from a roll of web through a printing couple, or through a plurality of printing couples in series, to a power driven rewind reel, the driving connections to the latter being interrupted simultaneously with the interruption of impression in the printing couple or couples. Specifically the printing couple and impression establishing and releasing mechanism illustrated are those shown in applicant's co-pending application Serial No. 209,284, filed May 21, 1938. In the present application the details of the mechanism shown in said patent and co-pending application will be described only with such particularity as is necessary for an understanding of the present invention.

As illustrated herein, the web W passes between the cooperating pressure rolls 1 and 3. These rolls may constitute the squeeze rolls of an immersion machine, or may constitute a printing or coating couple, the roll 1 for example, being a rotogravure print cylinder having the associated inking mechanism (not shown), and the roll 3 the cooperating impression cylinder.

Here the web after passing between the rolls

1 and 3 passes over a hot roll 5 for operating upon the web to dry the ink or coating material applied to it. After passing over the hot roll the web is guided to the rewind reel (not shown). When the web is passed in series through a plurality of rolls 5 1 and 3 as, for example, would be the case in a multi-color press of the type shown by the above mentioned patent, the apparatus shown in the application drawings may be considered as the last printing couple of the series. Each printing 10 or coating couple may have a hot roll 5 for drying the material applied by it to the web.

As shown, the machine comprises a pair of standards 7 rigidly connected at their upper portions by a transverse girder 9. On each standard is mounted a bearing 11 for rotatably supporting the end portions of the shaft 13 of the roll 1, which shaft at one end is shown as provided with a driving gear 15.

The roll 3, as illustrated, is rotatably mounted 20 on a non-rotating shaft 17, suitable collars 19 on the shaft restraining the roll against movement longitudinally thereof. As shown, this shaft at each end portion is fixedly carried at the end of a swinging arm 21, the opposite end of 25 each arm being pivoted on a pin 23 rigidly carried by the adjacent standard 7.

As shown, above the arms 21 is a rock shaft 25, opposite end portions of which are journalled 30 in the standards 7, and further journalled in lugs 27 carried by the girder 9. Carried by the rock shaft so as to rotate therewith are a pair of spaced arms 29. To the end portions of each arm 29 is pivotally connected the upper end of a link 31, a single pin 33 extending from one arm 35 to the other to provide the pivotal connection. At their lower ends the two links 31 are pivotally connected by a pin 35 to a block 37. Also rotatably carried by the rock shaft 25 between the arms 29 is a block 39, and slidably extending through a 40 perforation 41 (Fig. 4) in this block is a sleeve 43 rigidly connected at its lower end to the block 37, while at its upper end it carries a head 45 serving as an abutment for a compression spring 47, the block 39 serving as an abutment for the lower end 45 of this compression spring. Extending through the sleeve 43 is a screw-threaded rod 49 carrying upper and lower nuts 51 respectively bearing against the head 45 and block 37 so that the screw 50 may be adjusted vertically relative to the sleeve 43. At its lower end the screw-threaded rod 49 carries a head 53 connected to a bar 55, which bar extends between and is connected at opposite end portions to the two swinging arms 21.

By reason of the construction above described 55

when the parts are in the position shown by Figs. 1, 2 and 4 the arms 29 and links 31 serve as "toggle-links" to exert pressure between the rolls 3 and 1, the pin 33 under these conditions resting 5 against the sleeve 43 as a stop owing to the fact that the "toggle" is slightly beyond dead center position, as will be clear from Fig. 4. By rotating the rock shaft in the direction of the arrow on the gear 57 (Fig. 2) the pin 33 (Fig. 4) 10 will be moved to the right past its dead center position, whereupon further rotation of the shaft aided by the compression spring 47 will move the parts into the position shown by Fig. 3 to move the roll 3 away from the roll 1, that is to 15 say, if the rolls 1 and 3 constitute a printing couple, to "break impression." When the parts are in the position shown by Fig. 3 the compression spring will hold them there until the shaft is rotated in the opposite direction to reestablish 20 impression.

For rotating the rock shaft 25 the gear wheel 57, which is fixed to the shaft, has meshing therewith a pinion 59 journaled on the adjacent standard 7, which gear wheel may be rotated by 25 means of a hand lever 61.

The end of the rock shaft 25 opposite the gear wheel 57, as shown, fixedly carries a crank arm 63 to which is pivotally connected a link 65 for interrupting the drive for the rewind mechanism. 30 when the toggle is "broken" as just described, as will be clear from the above mentioned patent. Similarly the link 65 may be connected to crank arms 63 on other shafts 25 for similar printing couples or the like through which the web travels 35 so that impression will be interrupted in all of these printing couples at the same time as well as interrupting operation of the rewind mechanism.

The hot roll 5, as shown, is rotatably mounted 40 on a hollow non-rotating arbor or shaft 67 supported at opposite ends on the adjacent standards 7 by suitable supporting means carried by those standards as, for example, the brackets 69, bars 71 carried by those brackets, and further brackets 45 73 carried by the bars, the shaft 67 being carried at opposite ends by the last mentioned brackets.

The hot roll may be heated by non-rotating electric resistance elements 75, more or less diagrammatically illustrated in Fig. 1, carried by the 50 arbor 67, the energizing leads (not shown) for the resistance elements conveniently extending through the hollow of this arbor to the exterior thereof.

As illustrated, the rock shaft 25 adjacent each 55 of opposite ends thereof fixedly carries an upwardly extending arm 77, each of which, as shown by Figs. 2 and 3, is formed with a longitudinally extending slot 79. Projecting into each slot 79 is a shouldered pin 81 which, by means 60 of the nut 82, can be fixed in adjusted positions lengthwise of the slot. These pins serve to connect the ends of links 83 pivotally to the arms 77. Each link at its end opposite the pin 81 is pivotally connected at 85 to the end of the arm 87 of 65 a bell crank lever, the hubs 89 of which levers are rotatably mounted on the shaft or arbor 67. As shown, the other arms 91 of these bell crank levers carry at their end portions the opposite

ends of an arbor or shaft 93, which arbor rotatably supports a web engaging roller 95.

When the parts are in the position shown by Fig. 2, that is to say while the web is being fed, the roller 95 will be out of contact with the web. 5 When the shaft 25 is rotated, to cause the "toggle" to "break" and impression or the like to be interrupted, the arm 77 will be moved to the position shown by Fig. 3, which will cause the roller 95 10 to swing to its position shown by that figure, in which position the roller engages the web and lifts it off the hot roll 5 so that the web, which under these conditions is not fed, will not be burned or scorched by the hot roll. By adjusting the pin 81 lengthwise of the arm 77 the distance 15 the web is lifted from the hot roll may be regulated.

It will be understood that, within the scope of the appended claims, wide deviations may be made from the embodiment of the invention described without departing from the spirit of the invention. 20

I claim:

1. Apparatus of the character described having, in combination, means for feeding a web and applying wet ink or the like to it, which means includes a pair of cooperating rotatable rolls between which the web passes for feeding it, means for drying the web comprising a heated part to which the moving web is normally presented, means operative while said rolls are rotating for separating them for rendering them inoperative to feed the web, means for directly moving the web out of presented relation to said heated part, and coordinated control means for operating the last two mentioned means, said control means having a position in which it causes said rolls to be separated and the web to be moved out of presented relation to said heated part and another position in which it causes said rolls to be closed upon the web and the latter to be moved into presented relation to said heated part. 25

2. Apparatus of the character described having, in combination, a print roll and a cooperating pressure roll for feeding and applying ink or the like to a web passing between them, and means for bodily moving the pressure roll while said print roll is rotating for closing them upon the web to feed it and for separating said rolls for rendering them inoperative to feed the web, 50 means for drying the web comprising a heated roll over which the moving web passes in contact therewith, a movable device having a position in which it moves the web out of contact with said heated roll and another position in which it permits the web to contact said heated roll, and coordinated control means for actuating said means for moving said pressure roll and said movable device, said control means having a position in which said print and pressure rolls are 55 closed upon the web and said movable device is positioned to permit the web to contact said heated roll and another position in which said print and pressure rolls are in separated relation and said movable device is positioned to cause 60 said web to be moved out of contact with said heated roll.

LEROY Q. PRESBY.
